(57) **CLAIM**

The ornamental design for a key lockable double sided gate latch, as shown and described.

DESCRIPTION

FIG. 1 is a front view of a key lockable double sided gate latch showing my new design;

FIG. 2 is left view thereof;

FIG. 3 is a right view thereof;

FIG. 4 is a rear view thereof;

FIG. 5 is top view thereof;

FIG. 6 is a bottom view thereof;

FIG. 7 is a perspective view thereof; and,

FIG. 8 is another perspective view thereof.

The broken lines appearing in FIGS. 1 and 4 illustrate portions of the key lockable double sided gate latch that form no part of the claimed design.
